WORK-GUIDING MECHANISM FOR SEWING MACHINES

Walter Myers, Stratford, Conn., assignor to The Singer Manufacturing Company, Elizabeth, N. J., a corporation of New Jersey

Application December 30, 1943, Serial No. 516,158

15 Claims. (Cl. 112—2)

1

This invention relates to work-guiding mechanisms employed in connection with sewing machines for spiral stitching purposes, such as spirally stitching the brims of sailors' hats.

The invention has for an object to provide a work-shifting mechanism assembly unit with which sewing machine units may be conveniently or interchangeably associated.

Another object of this invention is to provide means facilitating accurate repositioning of a traveling work-guide, as for example in the event of thread breakage in spiral stitching operations.

Other and more specific objects of the invention will be apparent from the following description and claims.

The invention comprises the devices, combinations and arrangements of parts hereinafter described in connection with the accompanying drawings, which illustrate a preferred embodiment of the invention and in which:

Fig. 1 is a perspective view of a sewing machine unit supported by a base-unit which contains the improved work-guiding mechanism. Fig. 2 represents a vertical section of the work-guide carrier taken lengthwise of the guide-carrier adjusting spindle. Fig. 3 represents a fragmentary vertical section of the guide-carrier, taken substantially on the line 3—3 of Fig. 2 and showing a portion of a modified lead-screw. Fig. 4 is a top-plan view of the work-guide with the top plate of the work-guide removed and showing a portion of the lead-screw. Fig. 5 represents horizontal sections taken at different levels of the right hand end portion of the base-unit pedestal; the sections being taken in substantially the horizontal planes containing the axes of rotation of the respective shafts shown. Fig. 6 represents a vertical section of the intermediate shaft driving worm and taken on substantially the line 6—6 of Fig. 5. Fig. 7 represents a vertical section of the work-guide and its carrier, the section being taken in substantially the vertical plane containing the rotation-axis of the lead-screw. Fig. 8 represents a vertical section of a portion of the base-unit pedestal and of the sewing machine bed-plate, the section being taken in substantially the vertical plane containing the axis of rotation of the intermediate shaft which engages the lead-screw shaft.

The sewing machine unit illustrated in Fig. 1 of the drawings has a bed-plate 10, from one end of which rises the hollow standard 11 of a bracket-arm 12 which terminates in a head 13 and overhangs the bed-plate 10. While the stitch-forming and work-feeding mechanism of the sewing machine shown in the drawings is struc-

2

turally substantially the same as disclosed in the U. S. Patent of S. Zonis, No. 2,267,581, Dec. 23, 1941, it will be understood from the following description that other kinds and varieties of stitch-forming and work-feeding mechanisms could be employed without departing from the spirit and scope of the present invention.

As more fully shown and described in said prior Patent No. 2,267,581, the sewing machine illustrated has a vertically reciprocatory needle 14 and a complementary loop-taker 15; said loop-taker being rotated by suitable connections (not shown) with a bed-shaft 16 disposed at the under side and extending horizontally lengthwise of the bed-plate 10. The bed-shaft 16 is rotatably journaled in a ball-bearing 17 supported by the bed-plate 10 and, adjacent said ball-bearing 17, a peripherally grooved pulley 18 is secured by a screw 19 upon the end of the bed-shaft 16 which is disposed below the bracket-arm standard 11. Engaging the pulley 18 is a clip-belt 20 by means of which the bed-shaft 16 is rotated once for each complete reciprocation of the needle 14.

The work is advanced across the bed-plate 10 by a conventional feed-dog 21 which operates through a work-supporting throat-plate 22 and is opposed in its work-engaging movements by a spring-depressed presser-foot 23.

The sewing machine above generally described is removably supported upon a base-unit having a frame including a hollow pedestal 24 and a trough-shaped arm 25 extending laterally from the upper portion of the base 24 and free at its outer end. The arm 25 of the base-unit and the sewing machine bed-plate 10 together provide a free work-arm adapted to accommodate endless work.

Secured by screws 26 upon the front face of the pedestal 24 is a bracket 27 formed with spaced bearing bosses 28 and 29 having horizontally aligned apertures 30 and 31. Rotatably journaled in the bearing-apertures 30, 31 of the bracket 27 is a horizontally disposed shaft 32 extending lengthwise of the base-unit arm 25 and having one end portion thereof in the region of the free end of the work-arm freely suspended. The shaft 32 is held against endwise movement in the bearing-bosses 28 and 29 by suitable collars 33. The suspended portion of the shaft 32 is provided with a spiral thread 34 of slow lead to form a lead-screw; the spiral thread 34 extending from the free end of the shaft 32 and preferably terminating short of the bracket-boss 28. Adjustably secured upon the shaft 32, between the lead-screw thread thereof and the bracket-boss 28, is a stop-

collar 35, of which the function will be hereinafter described.

The end of the lead-screw shaft 32 opposite to the threaded end thereof is provided within the bracket-boss 29 with a worm-gear 36. In driving engagement with the under side of the worm-gear 36 is a worm 37 carried by the forward end of an intermediate shaft 38 disposed horizontally transverse to the shaft 32 and extending into an opening 39 provided in the bracket-boss 29. The intermediate shaft 38 is journaled eccentrically in a bearing-bushing 40 secured by a screw 41 for turning adjustment in an internal bearing-lug 42 of the pedestal 24. This construction not only provides for convenient assembly of the shafts 32 and 38 in the proper intermeshing relation of the worm-gear 36 and worm 37, but also facilitates replacement of the lead-screw-shaft 32.

Secured upon the rearward end of the intermediate shaft 38, by a screw 43, is a worm-gear 44 engaged by a driving worm 45, disposed above the worm-gear 44 and rotatably journaled upon a fixed stud 46. As illustrated in Figs. 5 and 6 of the drawings, the stud 46 is secured by a screw 47 in a wall of the pedestal 24 to extend inwardly from said wall in substantial axial alinement with the bed-shaft 16 of the sewing machine and in parallel relation to the lead-screw shaft 32. At its inner end, the worm 45 has a driven-member in the form of a flange 48 provided with a crank-pin 49.

The bed-shaft pulley 13 of the sewing machine has an internal hub 18'. Secured by a screw 50 upon the pulley-hub 18' is a recessed driver-member in the form of a collar 51 provided with a crank-pin 52 disposed to engage the crank-pin 49 of the worm 45, thereby to rotate said worm 45 with the bed-shaft 16. The described driving arrangement for the worm 45 provides for ready removal of the sewing machine unit from the base-unit and permits of convenient association of a sewing machine unit or different sewing machine units with the base-unit.

Slidably supported upon the threaded free end portion of the lead-screw shaft 32, for travel lengthwise of said shaft and, therefore, cross-wise of the line of feed of the sewing machine, is a work-guide carrier 53 having a lead-screw shaft receiving aperture 54. Extending forwardly from one end of the carrier 53 is a boss 55 having an aperture 56 extending transversely of the aperture 54 and connected therewith by a follower-clearance opening 57. Secured in the carrier-boss 55 by a screw 58, for turning adjustment, is a bearing-bushing 59 formed with a flange 60 in engagement with the front end of the carrier-boss 55. The bearing-bushing 59 is eccentrically provided with a bearing-aperture 61.

Rotatably journaled in the bearing-aperture 61 of the bushing 59 is a spindle 62 extending horizontally transversely of the shaft 32 and provided at its rearward end with a cylindrical head 63 held in frictional engagement with the inner end of the bushing 59. The spindle-head 63 comprises a pinion having teeth 64 formed to mesh with the lead-screw thread 34 of the shaft 32. Secured by a screw 65 upon the forward end of the spindle 62 is a knurled nut 66 having an axial cavity 67. Housed in the nut-cavity 67 is a coil-spring 68 interposed between the nut 66 and the bushing 59 and functioning to restrain the spindle 62 against rotation during stitching operations of the sewing machine. When the spindle 62 is thus restrained against rotation, the

pinion 63 functions as a follower-nut which is complementary to the lead-screw thread 34 in effecting feeding of the carrier 53 lengthwise of the shaft 32 during rotation of said shaft 32. However, the spindle 62 may be readily rotated by manual manipulation of the nut 66 when the shaft 32 is stationary, to attain accurately any desired position of the carrier 53 upon the shaft 32. As the lead-screw end portion of the shaft 32 is free of the supporting base 24, the carrier 53 may be conveniently applied to and removed from the shaft 32 endwise thereof.

Any suitable form of work-guide may be associated with the carrier 53. The tubular work-guide illustrated in Figs. 1, 4 and 7 of the drawings comprises adjacent bottom-plates 69 and 70 individually secured for adjustment relative to each other upon the carrier 53 by pairs of screws 71 and 72 passing freely through elongated countersunk slots 73 and 74 provided in and extending transversely of the respective plates. The plates 69 and 70 have segmentally curved side edges, and the relatively remote curved side edges of the respective plates are bent upwardly and backwardly to form flanges overhanging the plates, thereby to provide spaced and opposed edge-guides 75 and 76. Detachably supported by the overhanging side flanges of the plates 69 and 70, in spaced relation to said plates, is a top plate 77 having its front edge portion bent back upon itself to form a loop 78 entered by the front ends of said flanges. The right hand edge portion of the top-plate 77 is provided at the upper side thereof with a supporting and locating block 79 which is recessed to receive the flange of the bottom-plate 70, thereby to support and to locate the right hand edge of the top-plate 77 in spaced relation to the edge-guide 76. By this means, increased clearance is provided within the work-guide at the right hand side thereof, for work having a rib at one edge as in sailors' hat brims.

The described work-guide merely rests upon the bed-plate 10 of the sewing machine; the connection between the work-guide carrier 53 and the lead-screw shaft 32 permitting pivotal movement of the carrier 53 upon said shaft. This construction therefore provides for readily swinging the work-guide forwardly about the shaft 32 into an out of the way position.

While obviously capable of other uses, the present improvement is particularly well adapted for spirally stitching the brims of sailors' hats. The brim to be stitched is passed through the work-guide and is directed by the edge-guide 76 thereof during the feeding of the brim by the feed-dog 21 across the bed-plate 10. In the operation of the sewing machine, the work is fed past the stitch-forming mechanism, across the bed-plate 10, by the feed-dog 21 and is at the same time progressively shifted sidewise to the right by the rotating lead-screw 32.

In its sidewise travel, the work-guide carrier 53 ultimately engages the stop-collar 35 and is thereby arrested in a location of the work-guide predetermined by the setting of the stop-collar 35. This is permitted in the intermeshing relation of the spindle 63 and the lead-screw thread 34, by reason of the fact that the positive stopping of the carrier 53 by the collar 35 serves to overcome the rotation-restraining friction imposed by the spring 68 upon the pinion 63, thereby inducing the spindle 62 to rotate idly in the carrier 53.

In the modified form of construction illus-

trated in Fig. 3 of the drawings, a substitute rotary shaft 32' having a spiral lead-screw thread 34' is provided with a circumferential groove 30 at a location in the length of the shaft which corresponds substantially to the position of the left hand end of the stop-collar 35 above described. In this form of construction, the pinion 63 rides off the lead-screw thread 34' in the travel of the work-guide carrier 53, thereby bringing the carrier to rest.

Having thus set forth the nature of the invention, what I claim herein is:

1. A spiral stitching mechanism comprising, in combination, a base-unit including a supporting pedestal having a lateral arm free at one end, a lead-screw rotatably supported by said base-unit and extending lengthwise of said arm, a work-guide operatively connected to said lead-screw to derive lateral movements therefrom upon rotation of the lead-screw, a sewing machine unit removably supported upon said base-unit and having a frame including a bed-plate and a bracket-arm overhanging the bed-plate, said sewing machine unit containing stitch-forming and work-feeding mechanism including a rotary driver-member, a driven-member journaled upon said pedestal coaxially of said driver-member and disposed for rotating engagement by said driver-member, and operative connections with said driven-member for rotating said lead-screw.

2. A spiral stitching mechanism comprising, in combination, a base-unit including a supporting pedestal having a lateral arm free at one end, a lead-screw rotatably supported by said base-unit and extending lengthwise of said arm, a work-guide operatively connected to said lead-screw to derive lateral movements therefrom upon rotation of the lead-screw, a sewing machine unit removably supported upon said base-unit and having a frame including a bed-plate and a bracket-arm overhanging the bed-plate, said sewing machine unit containing stitch-forming and work-feeding mechanism including a rotary bed-shaft disposed below said bed-plate and substantially parallel to said lead-screw, a driver-member carried by said bed-shaft and having a crank-pin, a driven-member journaled upon said pedestal coaxially of said bed-shaft and having a crank-pin disposed for engagement by said crank-pin of the driver-member, an intermediate shaft rotatably journaled in said pedestal and extending crosswise of said lead-screw, worm and worm-gear connections between said driven-member and said intermediate shaft, and worm and worm-gear connections between said intermediate shaft and said lead-screw.

3. A spiral stitching mechanism comprising, in combination, a base-unit including a supporting pedestal having a lateral arm free at one end, a lead-screw rotatably supported by said base-unit and extending lengthwise of said arm, a work-guide operatively connected to said lead-screw to derive lateral movements therefrom upon rotation of the lead-screw, a sewing machine unit removably supported upon said base-unit and having a frame including a bed-plate and a bracket-arm overhanging the bed-plate, said sewing machine unit containing stitch-forming and work-feeding mechanism, a rotary driver-member carried by the sewing machine mechanism, a bearing-bushing extending crosswise of said lead-screw and supported by said pedestal for turning adjustment about its longitudinal axis, an intermediate shaft rotatably journaled eccentrically in said bearing-bushing, worm and worm-gear connections between said intermediate shaft and

said lead-screw, and operative connections for rotating said intermediate shaft from said driver-member.

4. A spiral stitching mechanism comprising, in combination, a base-unit including a supporting pedestal having a lateral arm free at one end, a lead-screw rotatably supported by said base-unit and extending lengthwise of said arm, a work-guide operatively connected to said lead-screw to derive lateral movements therefrom upon rotation of the lead-screw, a sewing machine unit removably supported upon said base-unit and having a frame including a bed-plate and a bracket-arm overhanging the bed-plate, said sewing machine unit containing stitch-forming and work-feeding mechanism including a rotary bed-shaft disposed below said bed-plate and substantially parallel to said lead-screw, a driver-member carried by said bed-shaft for rotation therewith, a driven-member journaled upon said pedestal coaxially of said bed-shaft and disposed for rotating engagement by said driver-member, a bearing-bushing extending crosswise of said lead-screw and supported by said pedestal for turning adjustment about its longitudinal axis, an intermediate shaft rotatably journaled eccentrically in said bearing-bushing, and lead-screw rotating gears connecting driven-member, intermediate shaft and lead-screw.

5. A work-guiding base-unit support for sewing machines, comprising, a pedestal having a lateral arm free at one end and adapted to support a sewing machine, a lead-screw shaft rotatably supported by said pedestal and extending lengthwise of said arm, said shaft having a threaded free end portion of its length disposed in the region of the free end of said work-arm, a crank-member supported by said pedestal for rotation about an axis substantially parallel to the axis of rotation of said lead-screw shaft, an intermediate shaft rotatably journaled in said pedestal and having gear connections with said crank-member and said lead-screw shaft, a work-guide carrier supported to travel lengthwise of said lead-screw shaft, and a follower-nut supported by said carrier and disposed in carrier-propelling engagement with the thread of said lead-screw shaft.

6. In a work-guiding device for sewing machines, a rotary shaft restrained against endwise movement and provided with a lead-screw thread, a work-guide carrier adapted to be propelled endwise of said shaft, a pinion rotatably journaled in said carrier and disposed in mesh with the lead-screw thread of said shaft, and means for restraining said pinion against rotation, thereby to convert said pinion into a follower-nut.

7. In a work-guiding device for sewing machines, a rotary shaft restrained against endwise movement and provided with a lead-screw thread, a work-guide carrier adapted to be propelled endwise of said shaft, a pinion rotatably journaled in said carrier and disposed in mesh with the lead-screw thread of said shaft, and friction means for restraining said pinion against rotation, thereby to convert said pinion into a follower-nut.

8. In a work-guiding device for sewing machines, a rotary shaft restrained against endwise movement and provided with a lead-screw thread, a work-guide carrier adapted to be propelled endwise of said shaft, a spindle rotatably journaled in said carrier and extending cross-wise of said shaft, said spindle having a peripherally toothed head in mesh with the lead-screw thread of said shaft, and means for restraining said spindle

against rotation, thereby to convert said head into a follower-nut.

9. In a work-guiding device for sewing machines, a rotary shaft restrained against endwise movement and provided with a lead-screw thread, a work-guide carrier adapted to be propelled endwise of said shaft, a bushing journaled in said carrier for turning adjustment about an axis transverse to the rotation-axis of said shaft, a spindle rotatably journaled eccentrically in said bushing and carrying a pinion in mesh with the lead-screw thread of said shaft, and means for restraining said spindle against rotation, thereby to convert said pinion into a follower-nut.

10. In a work-guiding device for sewing machines, a rotary shaft restrained against endwise movement and provided with a lead-screw thread, a work-guide carrier adapted to be propelled endwise of said shaft, a pinion in mesh with the lead-screw thread of said shaft and journaled in said carrier for rotation about an axis transverse to the rotation axis of said shaft, means providing for adjustment of said pinion toward and from said shaft, and means for restraining said pinion against rotation, thereby to convert said pinion into a follower-nut.

11. In a work-guiding device for sewing machines, a rotary shaft restrained against endwise movement and provided with a lead-screw thread, a work-guide carrier adapted to be propelled endwise of said shaft, a spindle journaled in said carrier for rotation about an axis transverse to the rotation-axis of said shaft, a pinion carried by said spindle and disposed in mesh with the lead-screw thread of said shaft, a manually rotatable nut carried by said spindle for rotating said pinion, and spring means for frictionally securing said spindle against rotation in said carrier, thereby to convert said pinion into a follower-nut.

12. In a work-guiding device for sewing machines, a rotary shaft restrained against endwise movement and provided with a lead-screw thread, a transversely apertured work-guide carrier, a

lead-screw shaft extending through one of the apertures of and slidably supporting said carrier, a spindle rotatably journaled in the other aperture of said carrier, a pinion carried by one end 5 of said spindle and disposed in mesh with the thread of said lead-screw, means carried by the other end of said spindle and disposed externally of said carrier for manually rotating said pinion, and means for securing said spindle against rotation, thereby to convert said pinion into a follower-nut.

13. In a work-guiding device for sewing machines, a rotary shaft restrained against endwise movement and provided with a lead-screw thread, 15 a work-guide carrier adapted to be propelled endwise of said shaft, a pinion rotatably journaled in said carrier and disposed in mesh with the lead-screw thread of said shaft, manually operable means for rotating said pinion, and means 20 for securing said pinion against rotation, thereby to convert said pinion into a follower-nut.

14. In a work-guiding device for sewing machines, a rotary shaft restrained against endwise movement and provided with a lead-screw thread, 25 a work-guide carrier adapted to be propelled endwise of said shaft, a pinion rotatably journaled in said carrier and disposed in mesh with the lead-screw thread of said shaft, yieldable means 30 for securing said pinion against rotation, and means limiting the travel of said carrier in one direction.

15. In a work-guiding device for sewing machines, a rotary shaft restrained against endwise movement and provided with a lead-screw 35 thread, a work-guide carrier adapted to be propelled endwise of said shaft, a pinion rotatably journaled in said carrier and disposed in mesh with the lead-screw thread of said shaft, yieldable means for securing said pinion against rotation, and a stop-member carried by said shaft 40 and disposed in the path of movement in one direction of said carrier.

WALTER MYERS.
